ATTORNEY

UNITED STATES PATENT OFFICE.

SIMON SCHEUER, OF NEW YORK, N. Y.

FAN.

SPECIFICATION forming part of Letters Patent No. 244,819, dated July 12, 1881.

Application filed February 2, 1881. (No model.)

To all whom it may concern:

Be it known that I, SIMON SCHEUER, of the city, county, and State of New York, have invented certain new and useful Improvements 5 in Fans, of which the following is a specification.

This invention relates to improvements in folding fans of that class in which one side piece of the handle-frame is swung around a 10 pivot at the upper end of the handle-frame through an entire circle, so as to open or close the web of the fan; and the invention consists of a folding web which is attached centrally to a pivot at the end of the handle-frame, one 15 side piece of which is provided with a rigid handle having a projecting shoulder or seat equal to the width of the folded web. The other side piece is adapted to swing on the pivot parallel to the fixed side piece through 20 an entire circle, and is locked to the shoulder of the handle by means of a centrally notched spring shield and a central projecting stud or button.

In the accompanying drawings, Figure 1 25 represents a side elevation of my improved fan in open position. Fig. 2 is an end view of the same folded; Fig. 3, a side view of the section of the handle-frame; and Figs. 4 and 5 are horizontal sections of the fan, both on line $x-x$, 30 Fig. 2, showing the same in folded and open positions.

Similar letters of reference indicate corresponding parts.

In the drawings, A represents the web, and 35 B B' B² the handle-frame, of my improved fan. The handle-frame B B' B² consists of a side piece, B, which is made in one piece with a solid handle, B². The second side piece, B', is made equal in length with the side piece B 40 and is pivoted to a fixed connecting-pin, a, at the outer end of the side piece B which pivot serves also as the center pin, around which the web A swings into an open or closed position. The end strips, D D', of the web A are connected respectively to the side pieces, B B', the end strip D' being attached rigidly to the side piece B' while the other swings between end lugs or stops, b, of a guide-casing, formed in a 45 projecting shoulder, d, of the handle B². The side piece B' is adapted to be swung on the end pivot, a, through an entire circle, and is locked to the solid shoulder d of the handle B² by means of a centrally-notched metallic plate or shield, E, which engages a fixed projecting

stud or button, e, of the side piece B'. The 55 shield E is rigidly attached to the face of the shoulder d and extended far enough above the same to engage the stud e of the side piece B'. The connecting pivot-pin a of the side pieces, B B', "gives" until the stud is engaged by the 60 central notch of the shield E. A recess, d', of the shoulder back of the shield serves to guide the side piece B' and to hold it steadily between shoulder and shield when locked.

The fan may be readily opened by releasing 65 the stud of the swinging side piece B' from the plate or shield and swinging it through an entire circle parallel to the fixed side piece B until the stud arrives again to the shield and is engaged by the same. The end strip D of 70 the web A swings during this motion of the side piece B' from one end lug, b, of the shoulder to the other. In closing the fan the same operation, but in a reverse order, is accomplished. The fixed end strip D' of the 75 side piece B' abuts, when the fan is opened, against the swinging end stud D and admits thereby the swinging of the side piece B' only toward the right in closing the fan and toward the left in opening the same. In this 80 manner the proper motion of the swinging side piece D' in opening or closing the fan is secured, and the handling of the fan rendered easy and certain.

Having thus described my invention, I claim 85 as new and desire to secure by Letters Patent—

1. As an improvement in fans, the combination of the web A, handle-section B B², having a recessed projecting shoulder, d d', and swinging side piece B', having projecting 90 stud e, with a notched plate or shield, E, secured to the shoulder of the handle-section, substantially as specified.

2. The combination of the web A, having end strips, D D', handle-section B B², having 95 a projecting shoulder, d, and end lugs, b b', and swinging handle-section B', having a projecting stud, e, with a locking-shield, E, secured to the shoulder of the handle-section, substantially as specified.

In testimony that I claim the foregoing as my invention I have signed my name, in presence of two witnesses, this 14th day of January, 1881.

SIMON SCHEUER.
